UNITED STATES PATENT OFFICE.

JOSEPH W. CASPER AND WILLIAM GERDER, OF SACRAMENTO, CALIFORNIA.

STEAM-MANGLE.

SPECIFICATION forming part of Letters Patent No. 686,385, dated November 12, 1901.

Application filed March 26, 1901. Serial No. 52,902. (No model.)

To all whom it may concern:

Be it known that we, JOSEPH W. CASPER and WILLIAM GERDER, citizens of the United States, residing at Sacramento, county of Sacramento, State of California, have invented an Improvement in Steam-Mangles; and we hereby declare the following to be a full, clear, and exact description of the same.

Our invention relates to an apparatus which is designed for ironing or mangling clothes.

It consists of the parts and the constructions and combinations of parts hereinafter described and claimed.

Figure 1 is a plan view of the mangle. Fig. 2 is a front end view of the same. Fig. 3 is a vertical cross-section. Fig. 4 is a detail of the feeding device. Fig. 5 is a section through a steam-chest on line $x x$ of Fig. 3. Fig. 6 is a detail showing a portion of the supporting periphery of the drum with its wire network of differing degrees of fineness.

The cylinders or drums A are provided with annular bands A', having spokes or spiders A² extending to a central shaft 2, and the peripheral covering of said drums is composed first of a coarse wire network of sufficient rigidity suitably fixed to the interior supporting annular bands A' and upon which network is stretched another finer network properly secured thereto. Overall this is a blanket or other suitable fibrous and elastic material a, which forms the surface upon which the material to be ironed is supported while being carried over the hot ironing-surfaces which are opposed to the cylinders, as will be hereinafter described. These cylinders are mounted upon shafts 2, and these shafts are journaled in the ends of the cross-bars 3 of T-shaped supports, which are fulcrumed, as at 4, while the vertical arms of the supports extend downwardly from the fulcrum-point and have toothed racks 5 at the lower end, which engage with pinions 6, mounted upon the shaft 7, so that by turning the pinions the racks will be moved in unison and the cross-bars 3 of the T-shaped supports with the cylinders will be tilted about the fulcrums 4. This will raise one cylinder and depress the other for the purpose of removing the blanket-surfaces from the hot ironing-surfaces to prevent scorching when not in use.

The pinions 6 may be rotated by any suitable or convenient means. In the present arrangement we have shown them as operated by a worm-gear 8, the shaft of which has a hand-wheel 9 at the upper end within convenient reach of an operator, so that by turning the shaft and worm the gear with which the worm engages will be turned, and as it is mounted on the same shaft with the pinions 6 the latter will also be turned.

The casings or irons opposed to the drum-surfaces consist of iron segments having a length about equal to that of the drums and a curvature on the same radius with the peripheries of the drums. These segments 10 and 11 are so mounted that the curvature of one incloses the lower half of one of the drums and the curvature of the other incloses the upper half of the other drum, so that clothes or material to be ironed will be carried between the first cylinder and its casing for about a half-revolution of the cylinder and then transferred to the upper half of the other cylinder and its casing.

Between the two cylinders is what is termed a "guide-plate" 12, the lower end of which is so hinged or attached that it is in line with the discharge end of the lower casing 10, and the upper edge of the guide rests against the surface of the second cylinder and beneath the receiving end of the casing 11, so that goods emerging from the casing of the first cylinder will be directed by the guide 12 directly into the space between the second cylinder and its casing. There will be no danger of wrinkling, folding, or tearing the goods, because the edge of the guide is in the direction of travel of the goods. Endless tapes b, passing around the drums, assist in guiding, said tapes passing under one of the cylinders and between the same and the corresponding casing or iron and thence passes over the other cylinder and between the same and the other casing or iron and finally passes over said last-named casing and the first-named cylinder, as shown in Fig. 3.

In order to provide the proper heat for the ironing-surfaces of the casings, we form steam chests or boxes 13 at the ends of the casings, and between these steam-chests extend tubes 14. These tubes are fitted into the holes bored in the steam-chests, and the ends of the tubes

are secured by screw-plugs 15, fitting corresponding threads in the interior of the tubes and having flanges upon the outer ends which may be screwed up against the outside of the 5 steam-chest, thus forming tight joints therewith. Any suitable means for inserting and removing these plugs may be employed, such as a central square socket for a wrench, or the flanges of the plugs may be made polygonal 10 to receive the similarly-shaped wrench. The tubes are perforated, as shown at 16, in line with surrounding channels 17 in the steam chests or boxes, so that steam admitted at one end—say at s, Fig. 1—into the live-steam 15 chest will pass through the holes 16 into the interior of the tubes 14 and, passing through the tubes, will be discharged through like passages and chests at the opposite end—say at t—thus providing for a constant flow of steam 20 of any degree of heat that may be found necessary or desirable. This serves to constantly heat the smooth metal surface of the interior of the casings 10 and 11, and the goods to be ironed, carried by the blanket-surface of the 25 revolving cylinders, are first caused to move over the ironing-surface of the first casing, which thus irons one side of the goods, and passing thence up over the second cylinder the other surface is presented to the second 30 casing, so that both sides are ironed in a single operation and the goods discharged at the outer side of the second cylinder.

The moisture in the clothes to be ironed continually passes through the blanket and 35 screen surfaces, and if not prevented would pass across the cylinders and deposit upon the opposite sides, thus forming a condensed body of moisture which will continuously drip and prevent the proper action of the ironing 40 apparatus. In order to overcome this difficulty, we divide our cylinders by longitudinal partitions or diaphragms, as at 18, extending radially from the axis to the periphery. Thus while the cylinder is turning so that 45 either of these quadrants or sections is passing through the heated casing any steam or vapor forced through to the interior of the cylinder may be discharged from the particular section in which it is and not be allowed 50 to pass across to the opposite side of the cylinder, where it might condense.

In order to feed the clothes and deliver them smoothly between the first cylinder and its casing, we employ a feed-table, as at 19, suitably located with relation to the cylinder. In 55 the present case we have shown it as supported upon frames, as 20, which are pivotally mounted in the frame of the machine by means of the shaft 21, and these frames carry a roller 60 22, the journal-boxes of which are slidably in guide-slots in the frame, one at each end, and are acted upon by springs 23, which hold the drum 22 yieldingly against the first ironing-cylinder of the apparatus. Above the drum 65 22 is a drum 24, the shaft of which is journaled in hinged arms 25, so that it may freely move with relation to the drum 22, upon which

it normally presses, and between these two drums the goods passing from the table 19 are delivered first between the drums 22 and 70 24 and next between the drum 22 and the drum A. A plate 26 is so disposed with relation to these drums as to prevent the goods adhering to the drum 22 and being returned beneath the drum, so as to be wrinkled or torn. 75 Tapes pass around the drum 22 and around rollers, as at 27, which rollers are so journaled with relation to a slot or opening in the plate 26 that the tapes lead away from the drum 22 around these rollers 27, thence backwardly 80 beneath the drum 22, and returning upon its under surface. The direction of the tapes is thus such that the goods are disengaged from the roller 22, to which they might otherwise adhere, and the edge of the goods following 85 the tapes and the plate 26 will be delivered between the periphery of the first drum A and the ironing-surface 10, after which the friction of the blanket or other fibrous surface upon the drum A will carry the goods smoothly 90 through the space between the drum and its opposing segmental ironing-face. The frames 20 being fulcrumed, as before described, upon the frame of the machine by means of the shaft 21, are adjusted to bring the drum 22 95 more or less closely to the ironing-drum A by means of a toothed pinion 28, fixed upon the pivoted shaft 21, and a screw or worm 29 which engages it, and is operated by a hand-wheel or other suitable attachment 30. By 100 turning this hand-wheel and screw the pinion will be turned and the frames 20 and the parts carried by them will be tilted as desired. This adjustment brings the drum 22 in proper relation with the ironing-drum A, and the 105 elasticity of the journal-box springs 23 allows a sufficient automatic adjustment of the drum 22 to accommodate the varying thicknesses of goods which are to be passed between the drums. The tilting device also removes the 110 table and feed mechanism from the cylinder A, so that the tapes may be easily removed and replaced, and the feed mechanism is also out of the way when the blanket is to be run on or off of the cylinder A. 115

Power to operate the machine may be communicated to any well-known or appropriate mechanism, the one herein shown including a pulley 4' on the shaft 4 and a series of intermeshing gear-wheels on the cylinder-shafts, 120 as shown in Figs. 1 and 2.

Having thus described our invention, what we claim as new, and desire to secure by Letters Patent, is—

1. In a mangle the combination of oppositely-revolvable drums and semi-inclosing heated casings upon opposite sides of the drums, centrally-fulcrumed frames in the outer ends of which the shafts of the drums are journaled, said frames having a lever extension, and means engaging said extension and by which said frames may be tilted so as to move the drums simultaneously with relation to their casings. 125 130

2. In a mangle the combination of oppositely-revolvble hollow drums having interior diaphragms forming separate compartments, centrally-pivoted frames in which the journal-shafts of the drums are carried, segmental casings inclosing opposite sides of the drums, means for heating said casings, connections with the pivoted frames including toothed racks on said pivoted frames and gearing engaging said racks whereby said frames may be tilted to cause the drums to approach or recede from their casings simultaneously. 60
3. In a mangle, the oppositely-revolvble hollow compartment-drums having the periphery composed of rigid meshes and a permeable outer covering, and the heated segmental casings, partially inclosing opposite sides of the drums, T-shaped frames centrally pivoted in main frames at the ends of the apparatus, journal-boxes in said T-shaped frames in which the drum-shafts are turnable, racks formed upon the vertical bars of the T-shaped frames, pinions mounted upon a shaft and engaging said racks, and means for turning the pinion-shaft and moving the racks, said T-shaped frames being adapted to adjust the position of the drums simultaneously with relation to the casings. 70
4. In a mangle the combination of revolvble drums, having the periphery composed of rigid foraminous material and a permeable outer covering, said drums having, also, internal diaphragms forming separate compartments, a concaved segmental casing within which each drum is turnable, said casings having smooth interior ironing-surfaces, said casings inclosing parallel steam-pipes extending from end to end within the casings, steam chests or boxes with which the ends of the pipes are connected, one of said boxes being connected with a source of steam-supply, and the other with an outlet-passage. 80
5. In a mangle, the concaved casing having an interior ironing-surface, parallel tubes extending from end to end through the casing, hollow segmental steam-boxes having approximately the same curvature as the casings and into which the tubes are fitted, channels formed in the interior curvature of said steam-boxes, and holes made in the tubes coincident with said channels whereby steam is admitted into and discharged from the tubes. 90
6. In a mangle, a concaved casing having an interior ironing-surface, parallel tubes extending through said casing, channeled steam-boxes at the ends of the casing into which the tubes enter, said tubes having holes coincident with the channels for the admis- 100
- sion and discharge of steam, and screw-plugs fitting the interior of the tube ends having flanges or heads which screw up against the outside of the steam-boxes to lock the parts in position. 105
7. The combination in a mangle of the drum and casing, and feeding devices consisting of a pivoted feed-table, a revolvble roll to receive the goods therefrom, said roll coming in contact with the ironing-drum, and a supplemental pressure-roll contacting therewith. 110
8. In an ironing-machine, the combination with a series of horizontal revolvble drums, and concaved ironing-surfaces adjacent thereto, of a means by which the article to be ironed is fed to said drums, said means including a pivoted table, a revolvble roll over which the material passes from the table, a slotted frame in which the journal-boxes of the roll are carried, and springs pressing against said boxes whereby the roll is adjustably held in contact with the ironing-drum. 120
9. In an ironing-machine, the combination with a series of horizontal revolvble drums, and concaved ironing-surfaces adjacent thereto, of a means by which the article to be ironed is fed to said drums, said means including a pivoted table, rolls between which the material passes from the table, and by which it is delivered between the drum and the casing, endless tapes passing around the roll, and supplemental guide-rolls, and an apron in conjunction therewith by which the material is prevented from returning around the roll. 130
10. The combination in a mangle of a revolvble foraminous drum with blanket-covered surface, a heated concave within which the drum revolves, a feed-table and a spring-pressed roller carried thereby, an adjustable roller between which and the first named, the goods pass from the table, and thence between said first-named roller and the main ironing-drum, guide-rollers journaled beneath the first roller and adjacent to the main drum, tapes passing around the feed and guide rolls to detach the material, and a plate or apron to direct the material between the drum and the concave. 140

In witness whereof we have hereunto set our hands.

JOSEPH W. CASPER.
WILLIAM GERDER.
